UNITED STATES PATENT OFFICE

2,600,657

TIE CASE

Bryan S. W. Jones, El Monte, Calif.

Application November 4, 1949, Serial No. 125,440

2 Claims. (Cl. 206—7)

1

The present invention relates to cases generally, but more particularly to a type of case adapted to hold ties, such as the well-known four-in-hand ties.

An object of the invention is the provision of a case adapted to hold a series of ties in compressed condition and in such a manner that the ties do not pyramid, bulkiness is reduced, and many ties may be accommodated within a case of substantial thinness.

A further object is the provision of a case so formed as to receive four-in-hand ties and to hold said ties in position against shifting and in such a manner that ties are pressed.

A further object is a provision of a case for holding ties of any character which is inexpensive in cost of manufacture, slightly in appearance, and generally superior to devices for holding ties now known to the inventor.

Other objects of the invention will be given in more detail in the general description.

In the drawing:

Figure 1 is a perspective view of the improved tie case, and

Figure 2 is a cross-sectional view on the line 2—2 of Figure 1.

Referring now to the drawing, the improved device of the invention is shown as an entirety in Figure 1 and the same includes a case 1 of elongated form, having cover or side portions 2 and 3, which fold together along line 4, and which portions 2 and 3 are adapted to be secured together by any suitable means, such as a zipper 5. The construction is such that both portions 2 and 3 are provided with marginal walls 6 and 7, which carry along the upper edges thereof zipper teeth 8, which are laced together by an element 9 of the zipper. However, any other fastening means may be utilized.

Within the case are a plurality of leaves 10, 11, 12 and 13. Any number of leaves may be utilized, the leaves shown being for illustrative purposes only. Leaves 10 and 13 are in one sheet as likewise are leaves 11 and 12. The sheets are folded along their transverse centers and attached along the line 4 of the case by stitching or other means. Leaves 10 and 11 are secured together on a bias or oblique line as shown at 14, and leaves 12 and 13 are secured together on a bias or obliquely at 15. The space included between leaves 11 and 12 is unobstructed by any bias securing means.

If other leaves are to be added, there is a duplication of the four leaves 10 to 13 inclusive, which leaves would be secured along the trans-

2

verse line of division as leaves 11 and 12. In other words, each addition requires four leaves. Hence, any desired number of leaves can be utilized, depending upon the number of ties to be carried within the case.

The operation, uses, and advantages of the invention are as follows:

If we assume the use of four leaves of the character shown, there is placed between said leaves, 10 four-in-hand ties which have been folded, the tie shown at 16 is folded so as to lie between leaves 11 and 12. The tie shown at 17, which has been folded, rests in a pocket between leaves 12 and 13, and tie 18 is positioned in a pocket between leaves 10 and 11. The bias line of connection between leaves 10 and 11, 12 and 13, will, when the leaves are brought together, cause the ties under gravity to have one edge thereof engage the bias line in each instance, while the tie at 16 will lie adjacent the longitudinal line of stitching which connects said leaves with the case. Thus the folded ends of the ties will be in staggered relationship, and this assures that the ties will not directly overlie at the thickest portion thereof. The general appearance of the folded ties will be as shown in Figure 2, in cross-section, hence bulkiness and undue thickness is prevented. A case having eight leaves and holding eight or nine ties could be less than one inch in thickness.

The space included between the inner surface of the case sides 2 and 3 and the leaves may be utilized for holding ties.

When the case of the type shown in Figure 1 is laced, suitable pressure exists between the covers, sufficient to press the ties positioned therein. This keeps the ties in good condition. The case of the type shown is ideal for the traveler as it holds many ties without bulkiness.

The case, in addition to being adapted for ties, is also adapted for other wearing apparel, such as women's scarves, gloves and belts.

I claim:

1. A case for holding ties comprising at least two sheets, each of which has end and side edges, said sheets being longitudinally hinged together along their transverse centers to provide four leaves, two leaves in each instance being secured together on a bias to thereby provide an unbiased connection between two of said leaves, said bias in each instance extending from adjacent end edges of two leaves to the longitudinal hinged portion for said leaves.

2. In a case for ties, two substantially rectangular sheets, each having end and side edges and

secured together longitudinally on a median line between the side edges of said sheets, forming two leaves at each side of said median line, each of said two leaves being secured together on a line extending from one end of said leaves on a bias to said median line, and forming a pocket in each pair of said leaves open at the side edges of said leaves.
